BRAKING MECHANISM

Noel S. Reynolds, St. Louis, Mo., assignor to
Joseph J. Hagen, St. Louis, Mo.Application March 17, 1937, Serial No. 131,394
Renewed May 31, 1938

13 Claims. (Cl. 188—79.5)

My invention relates to braking mechanism and more particularly to improved means for adjusting the connection or joint between adjacent ends of two brake shoes.

- 6 One of the objects of my invention is to provide an adjustable connection between adjacent ends of two brake shoes which will permit free shifting of the connection with the shoes when they are applied to and released from the drum.
- 10 Another object of my invention is to provide a floating adjustable wedge means for cooperation with the guided connecting plungers between the ends of two brake shoes which will not oppose free movement of the plungers and which may be employed either as original equipment or as a
- 15 replacement for other types of adjusting means now found on commercially used brake assemblies.

Still another object of my invention is to provide an adjustable connection between two brake shoes which will permit the connection to shift with the shoes in one direction of rotation of the drum so that the leading or primary shoe in this direction of drum rotation will apply force to the secondary shoe but which will act as an anchor means for the leading or primary shoe in the other direction of rotation of the drum and not permit this shoe to apply force to the other shoe.

30 Other objects of my invention will become apparent from the following description taken in connection with the accompanying drawing in which Figure 1 is a side view of a brake assembly embodying my improved adjustable connection between one pair of adjacent ends of the shoes; Figure 2 is a cross-sectional view of the connection; Figure 3 is an end view of the adjusting wedge; and Figures 4 and 5 are cross-sectional views similar to Figure 2, showing modified constructions.

40 Referring to Figures 1 to 3, the braking assembly shown comprises the usual backing or dust plate 1 secured to a fixed part of the vehicle and enclosing the open side of the drum 2 fastened to the wheel for rotation therewith. Two brake shoes 3 and 4 are mounted within the drum in end-to-end relation with one pair of adjacent ends adapted to cooperate with the anchor post 5 carried by the backing plate.

45 These ends of the shoes are actuated into engagement with the drum by a slidable cam 6 cooperating with roller 7 carried by the webs of the shoes, the cam having an enlarged opening for receiving the anchor post and permitting the cam to float. The cam is moved by the arm 8

on a rotatable shaft 9 journaled in the backing plate and the shoes are held in retracted position against the anchor post by the spring 10.

5 The pair of adjacent ends of the shoes opposite the actuated ends are connected together by my novel adjustable connection permitting shoe 3 to transmit force to shoe 4 when the shoes are engaged with the drum and at the same time providing means to take up the shoes for lining wear. A casing 11 is secured to the backing plate 10 between the shoe ends and provided with tubular guideways 12 and 13 spaced on opposite sides of a bore or chamber 14. The guideway 12 has slidably mounted therein a plunger 15 which engages the end of shoe 3 and is provided with a flat inclined surface 16 on its end projecting into bore 14. Similarly, guideway 13 has slidably mounted therein a plunger 17 which engages the end of shoe 4 and is provided with a flat inclined surface 18 on its end projecting into bore 14. 20 Within bore 14 is a bolt 19 and secured on its end is a flanged part 20 having a serrated surface 20' for engagement with the sides of the plungers opposite the inclined surfaces. A wedge member 21 (Figure 3) is threaded on the bolt 25 and its flat surface 22 cooperates with inclined surface 16 and its flat surface 23 cooperates with inclined surface 18. The axis of the wedge member is eccentric to the axis of the bolt and the diameter of the wedge is less than that of bore 14 30 in order to permit the wedge and bolt to move with the plungers and relatively to casing 11. The bolt 19 projects through an oversized opening 24 in casing 11 to the exterior of the backing plate and is provided with a wrench receiving 35 head 25. A closure washer 26 of a suitable material is employed to keep dust and dirt from entering opening 24, the washer being held in position by a spring 27 interposed between it and the wedge.

40 In the brake assembly shown, the drum normally rotates in the direction indicated by the arrow, which rotation corresponds to the forward direction of the vehicle. When the shoes are disengaged from the drum, it is desired that 45 wedge 21 be positioned at the side of the bore toward the leading shoe 3 in order that the wedge and bolt may be free to shift with the plunger when the shoes are engaged with the drum. To insure that the wedge assumes this 50 normal position, a relatively light spring 28 is positioned on the outer end of plunger 15 between a washer 29 and casing 11. A spring 30 of greater strength than spring 28 is also employed between the shoes to maintain the latter in 55

engagement with the plungers and the plungers in engagement with the wedge. Thus it is seen that with the spring 38 functioning to hold the parts indicated in engagement the force of spring 5 28 will be effective to normally maintain these parts in the position shown in Figure 2.

With my improved adjustable connection embodied in a brake assembly of the type described, it is readily seen that when the shoes are applied 10 to the drum and the latter is rotating in the direction indicated by the arrow, the leading shoe 3 will be able to have slight circumferential movement with the drum and by means of the connecting plungers apply pressure to shoe 4 which 15 will anchor on post 5. The adjusting wedge and bolt freely float with the plungers and because of this, there is no binding action which will in any way resist or prevent the plungers from moving to thereby permit release of the shoes, the plungers, adjusting wedge and bolt will move freely 20 back to their normal positions (Figure 2) under the action of spring 28.

When the shoes are applied to the drum and the direction of rotation is opposite that indicated by 25 the arrow, shoe 3 will be forced into engagement with the drum but shoe 4 will not be able to apply force thereto through the connecting plungers as the wedge will be in engagement with casing 11 and because of this, it will act as an anchor for 30 shoe 4. The brake, under these conditions, will be an ordinary two-shoe brake in which shoe 4 will act as a pivoted "forward" shoe and shoe 3 as a pivoted "reverse" shoe instead of as a two-shoe "servo" brake as is the case when the drum is 35 rotating in the direction indicated by the arrow.

When it is desired to adjust the shoes to take care of lining wear, bolt 25 need only be turned in the proper direction to cause the wedge member 21 to be moved closer to the flange part 20. This 40 moves the plungers apart and sets the shoes closer to the drum. The flat surfaces 22 and 23, during the rotation of the bolt, prevent the wedge member from rotating with the bolt and serrations 20' assist in holding the bolt in adjusted position.

45 In Figure 4 I have shown a slightly modified construction of the adjusting device. The casing 11 and plungers 15 and 17 are the same as previously described. Within bore 14 is positioned a cup-shaped member 31 having aligned openings 32 and 33 therein for receiving the inner ends of the plungers. The open end of member 31 has threaded therein a wedge member 34 which is provided with a frusto-conical end for cooperating with the flat inclined surfaces of the plungers. The cup-shaped member has its axis 50 eccentric to the axis of the wedge and normally engages the side of the casing toward the leading shoe 3 under the action of spring 28. The wedge member 34 is provided with a tool receiving socket 34' whereby a suitable tool may be inserted 55 through opening 24 in the casing to move the wedge relatively to the cup-shaped member 33 to thereby adjust the plungers and consequently the shoes. A plug 35 is employed to close opening 24 to prevent entry of dirt and water. The operation 60 of the brake with this modified construction embodied therein is the same as previously described.

In Figure 5 I have shown still another modified 70 adjusting device which is substantially the reverse of that shown in Figure 2. In this construction plungers 15 and 17 are positioned in the casing with their flat inclined surfaces reversed. The bolt 36 has secured to its inner end the frusto-conical wedge member 37 which engages the flat

5 inclined surfaces 16 and 18 of the plungers. The bolt also has threaded thereon member 38 which has its axis eccentric to that of the bolt so that one of its sides will normally engage the casing under the action of spring 28. The member 38 is 10 provided with suitable grooves 39 for receiving the plunger and also preventing its rotation with the bolt. The conical surface of the wedge is formed with serrations 40 to assist in holding the wedge in adjusted position. When bolt 36 is 15 turned, the wedge will be moved toward or away from member 38, in accordance with the direction of rotation of the bolt, to provide proper adjustment of the shoes through the plungers. The 20 operation of the brake with this adjustable connection embodied therein is the same as previously described.

From the foregoing description of the preferred embodiment of my invention and the modified constructions, it is apparent that I have devised 25 an adjustable connection in which the adjusting means will not in any way resist or prevent the free movement of the plungers so that the leading shoe will apply its full force to the secondary shoe when the drum is rotating in one direction. It is 30 also apparent that the constructions are very well adapted for replacement use on brake assemblies wherein the plungers are not permitted to float because the adjusting wedge is fixed to casing 11 or on braking assemblies in which the wedge is so 35 mounted in casing 11 that it will bind on the wall of the casing and resist free shifting of the plungers during braking or during release of the 40 shoes.

Being aware of the possibility of modifications 35 in the particular structure herein described without departing from the fundamental principles of my invention, I do not intend that its scope be limited except as set forth by the appended claims.

Having fully described my invention, what I 40 claim as new and desire to secure by Letters Patent of the United States is:

1. In braking mechanism, a support, a brake drum, a pair of shoes positioned in end-to-end relation in the drum, means for expanding one 45 pair of adjacent ends of the shoes, a stationary guide carried by the support between the other pair of adjacent ends, shiftable plungers in the opposite ends of the guide and engaging the ends of the respective shoes, said plungers having inclined surfaces on their inner ends, a wedge engaging the inclined surfaces of the plungers, a member engaging the sides of the plungers opposite the inclined surfaces, and means for moving 50 said wedge and member relatively toward or away from each other, said wedge, member and moving means being movable as a unit with the 55 plungers.

2. In braking mechanism, a support, a brake drum, a pair of shoes positioned in end-to-end 60 relation in the drum, means for expanding one pair of adjacent ends of the shoes, a stationary guide carried by the support between the other pair of adjacent ends, shiftable plungers in the opposite ends of the guide and engaging the 65 ends of the respective shoes, said plungers having inclined surfaces on their inner ends, a wedge engaging the inclined surfaces of the plungers, a member engaging the sides of the plungers opposite the inclined surfaces, means for moving 70 said wedge and member relatively toward or away from each other, said wedge, member and moving means being movable as a unit with the 75 plungers when the plungers move in one direction, and spring means for normally biasing said

wedge and member to a position where one of them will engage the guide and prevent the plungers from moving as a unit in the other direction.

5. 3. In braking mechanism, a support, a brake drum, a pair of shoes positioned in end-to-end relation in the drum, means for expanding one pair of adjacent ends of the shoes, a stationary guide carried by the support between the other 10 pair of adjacent ends, shiftable plungers in the opposite ends of the guide and engaging the ends of the respective shoes, wedge means between the opposite ends of the guide and carried by the plungers for adjusting the distance between the 15 plungers, said wedge means being movable with the plungers and between the ends of the guide, means carried by and shiftable with the wedge means and plungers, and adapted to operate said wedge means to effect said adjustment of the distance between the plungers, and spring means for 20 normally biasing said wedge means into engagement with one end of said guide.

4. In braking mechanism, a support, a brake drum, a pair of shoes positioned in end-to-end 25 relation in the drum, means for expanding one pair of adjacent ends of the shoes, a stationary guide carried by the support between the other pair of adjacent ends, shiftable plungers in the opposite ends of the guide and engaging the ends 30 of the respective shoes, wedge means between the opposite ends of the guide and carried by the plungers for adjusting the distance between the plungers, said wedge means being movable with the plungers and between the ends of the guide, 35 means carried by and shiftable with the wedge means and plungers, and adapted to operate said wedge means to effect said adjustment of the distance between the plungers, a spring connecting said shoes, and a second spring surrounding one 40 of said plungers and engaging the guide for normally biasing said wedge means into engagement with one end of the guide.

5. An adjusting device for cooperation with a pair of brake shoe connecting plungers mounted 45 in spaced guides and having adjacent ends provided with inclined surfaces, said device comprising a threaded bolt, a shoulder carried by the end of the bolt and restrained against axial movement on the bolt, and an annular wedge member 50 threaded on said bolt and of a diameter less than the distance between the plunger guides, said wedge member having its axis eccentric to the axis of the bolt and being provided with flat beveled surfaces on opposite sides of its axis and facing the annular shoulder for cooperation with the inclined surfaces of the plungers, said beveled surfaces lying in planes having the same angular 55 relation to the axis of the bolt.

6. An adjusting device for cooperation with a 60 pair of brake shoe connecting plungers mounted in spaced guides and having adjacent ends provided with inclined surfaces, said device comprising a threaded bolt, a frusto-conical member secured against axial movement to the end of the bolt and having its axis coinciding with the axis of the bolt and its base positioned at the end of the bolt, and an annular member threaded on said bolt and of a diameter less than the distance between the plunger guides, said annular member having its axis eccentric to the axis of the 65 bolt.

7. An adjusting device for cooperation with a 70 pair of brake shoe connecting plungers mounted in spaced guides and having adjacent ends provided with inclined surfaces, said device com-

prising a threaded bolt, a frusto-conical member secured to the end of the bolt and having its axis coinciding with the axis of the bolt and its base positioned at the end of the bolt, and an annular member threaded on said bolt and of a 75 diameter less than the distance between the plunger guides, said annular member having its axis eccentric to the axis of the bolt and the surface thereof facing the frusto-conical member being provided with two opposed radially extending grooves for receiving the ends of the plungers.

8. An adjusting device for cooperation with a pair of brake shoe connecting plungers having adjacent ends provided with inclined surfaces, said device comprising a cup-shaped member 15 provided with threads on its inner wall and having openings in opposed sides thereof for receiving the ends of the plungers, and a member threaded in the cup-shaped member and provided with a conical surface on its inner end. 20

9. An adjusting device for cooperation with a pair of brake shoe connecting plungers having adjacent ends provided with inclined surfaces, said device comprising a cup-shaped member having its internal wall eccentric with respect 25 to the external wall, said internal wall being provided with threads and opposed sides of said cup-shaped member having openings for receiving the ends of the plungers, a member threaded in the cup-shaped member and provided with a 30 conical surface on its inner end, and tool receiving means at its outer end.

10. In braking mechanism, a combined adjustable connecting device and anchor for a brake assembly having a pair of brake shoes and comprising a fixed casing provided with spaced guides, 35 slideable plungers in said guides, a wedge engaging the plungers, a member cooperating with the plungers on the sides opposite those engaged by the wedge, and threaded means for relatively 40 moving the wedge and member axially toward or away from each other, said member having its axis eccentric to the axis of the threaded means and normally adapted to engage one of said spaced guides. 45

11. In braking mechanism, a combined adjustable connecting device and anchor for a brake assembly having a pair of brake shoes and comprising a fixed casing provided with spaced guides, slideable plungers in said guides, a wedge engaging 50 the plungers, a member cooperating with the plungers on the sides opposite those engaged by the wedge, and a threaded bolt extending to the exterior of the guide for relatively moving the wedge and member toward or away from each other, said wedge being provided with means preventing its rotation with the bolt and with an eccentric part adapted to normally engage one 55 of said guides and said wedge, member and bolt adapted to be movable with the plungers as a 60 unit.

12. An adjusting device for cooperation with a pair of brake shoe connecting plungers having adjacent ends provided with inclined surfaces, said device comprising a wedge for engaging the 65 inclined surfaces of the plungers, a member engaging the sides of the plungers opposite the inclined surfaces and having a threaded opening, and means for moving said wedge and member relatively toward and away from each other and 70 comprising a threaded portion carried by said wedge for cooperating with the threaded opening in the member and means for rotating the wedge and threaded portion.

13. An adjusting device for cooperation with a 75

pair of brake shoe connecting plungers having adjacent ends provided with inclined surfaces, said device comprising a cup-shaped member provided with threads on its inner wall and having openings in opposed sides thereof for receiving the ends of the plungers, a wedge member for

cooperating with the inclined surfaces of the plungers, and means for moving the wedge member relative to the cup-shaped member and comprising means associated with the wedge member and the threads of the cup-shaped member. 5
